UNITED STATES PATENT OFFICE.

WILLARD S. PAIN, OF MERIDEN, CONNECTICUT, ASSIGNOR TO THE AEOLIAN CO., OF NEW YORK, N. Y., A CORPORATION OF CONNECTICUT.

MACHINE FOR CUTTING MUSIC-SHEETS FOR MECHANICAL MUSICAL INSTRUMENTS.

SPECIFICATION forming part of Letters Patent No. 717,759, dated January 6, 1903.

Application filed May 24, 1901. Serial No. 61,694. (No model.)

To all whom it may concern:

Be it known that I, WILLARD S. PAIN, of Meriden, in the county of New Haven, State of Connecticut, have invented a new and useful Improvement in Machines for Cutting Music-Sheets for Mechanical Musical Instruments, of which the following is a specification.

A certain class of mechanical musical instruments are provided with what are called "music-sheets," consisting of sheets, generally of flexible paper, perforated so as to serve as valves controlling the admission of air to pneumatic apparatus regulating the operation of the sound-producing devices. Usually these sheets are rolled upon rolls termed "music-rolls," which are detachably connected with a musical instrument, so that one music-sheet may readily be substituted for another. Such music-sheets are generally cut by machines in which is used a stencil-sheet having the perforations necessary for the music-sheets and serving as a guide for the cutting of the music-sheets themselves.

My present improvement relates to machines using such stencil-sheets and cutting the music-sheets.

A machine embodying this improvement will be described, and then the novel features will be pointed out in the claims.

In the accompanying drawings, Figure 1 is a side elevation of a machine embodying the improvement. Fig. 2 is a plan or top view of the same with certain portions broken away to economize space. Fig. 3 is an enlarged elevation of certain parts on the opposite side of the machine from Fig. 1. Fig. 4 is an inverted plan or bottom view of certain parts upon the same scale as Fig. 3. Fig. 5 is a rear elevation of certain parts illustrated in Fig. 4. Fig. 6 is a vertical longitudinal section of certain parts. Fig. 7 is a side elevation of certain parts shown in Figs. 3, 4, and 5. Fig. 8 is an end elevation of certain parts illustrated in sectional elevation in Fig. 6.

Similar letters of reference designate corresponding parts in all the figures.

A designates a roller supported removably in bearings formed in uprights *b*, comprised in the framework *B* of the machine. This

roll may be removed to enable another to be substituted for it, and it is provided with a crank *a*, shown as secured to one of its journals by means of a set-screw, so that the crank may be readily removed. The purpose of the crank is to rotate the roller in a reverse direction to that in which it turns during the operation of the machine.

C designates a stencil-sheet which is to be used as a guide in cutting a large number of superimposed sheets of paper or like material in the manufacture of music-sheets for mechanical musical instruments. The stencil-sheet passes around a guide-pulley *c*, journaled in a portion of the framework *B* of the machine, and thence it passes around a cylinder *D*, which has ends *d*, fitting loosely upon a shaft *D'*, journaled in the framework *B* of the machine. The cylinder *D* is connected by brackets *d'* with the framework *B* of the machine, so that the cylinder will be prevented from rotating.

Upon the shaft *D'* are affixed toothed feed-wheels *d²* *d³*. The cylinder *D* may advantageously be a foot in circumference, and the pitch-line of the sprocket-wheels will correspond with it. When of such proportions, the sprocket-wheels will have twelve teeth.

Affixed to one of the journals of the shaft *D'* is a ratchet-wheel *D⁴*, and combined with that ratchet-wheel is a pawl *d⁵*, carried by a pawl-lever *d⁶*, oscillated by the rod *d⁷* of an eccentric *d⁸*, affixed to the main driving-shaft *E* of the machine, the latter being journaled in the framework *B*.

One of the journals of the shaft *D'* has combined with it a friction device *d⁹*, of suitable construction, for preventing the shaft *D'* from receiving any motion other than that which may be imparted to it by the pawl *d⁵*.

After passing around the cylinder *D* the stencil-sheet passes to and around a take-up roller *G*, journaled in the framework *B* of the machine and rotated by a belt *g* from any suitable source of power. This belt will preferably be loose enough to permit of slippage of the take-up roller *G* as the winding of the stencil-sheet upon the latter materially increases its effective diameter. Any equivalent means for preventing slippage may be used.

H designates a horizontally-reciprocating bar working upon pins h , supported by the framework B of the machine. Its reciprocations are produced by eccentrics h' , affixed 5 to the main driving-shaft E. With the bar H are combined a number of feelers I, which pass through holes in the bar H and also through holes in a bar J, fastened to the framework B of the machine. Rearward of the bar 10 H they are provided with collars i. At those ends which project beyond the bars J these feelers I are connected with the upper arms of levers K, which are fulcrumed upon a bar k, supported by the framework B of the machine, 15 and have their lower arms pivotally connected to rods L. The rods L are connected to rods L'. The connection may be made by a hook on the rod L engaging with pins on the rods L'. The rods L' pass through a horizontal bar L², working vertically in slide- 20 ways formed in the framework B of the machine. It is reciprocated up and down by eccentrics L³, mounted upon the main driving-shaft E. The rods of these eccentrics are 25 each divided into two sections and connected by spanners l³, these spanners consisting of rods having intermediate of their ends milled flanges and their two end portions reversely screwed thereto. Provision is thus afforded 30 for changing the position of the bar L².

The rods L' are connected to springs L⁴, which are also connected to a stationary bar L⁵, secured adjustably by screws l to the framework B of the machine, so that the tension of the springs may be varied. 35

The rods L' have in their undersides notches l', and below these bars the bar L² is fitted with vertical punches M, having heads of a diameter corresponding to the length of the notches l' in the rods L'. Whenever the rods 40 L' are in such position that their notches l' are over the heads of the punches M, the descent of the bar L² will not cause the descent of the punches; but whenever the notches l' of the rods L' are out of line with the heads of 45 the punches M, the descent of the bar L² will cause the operation of the punches.

It will be readily seen that whenever a perforation of the stencil-sheet C comes opposite 50 the feelers I the latter will be free to enter those perforations under force exerted by the springs L⁴. The cylinder D is slotted opposite the lines of perforations in the stencil-sheet, and it contains behind these perforations a stop, here shown as made in the form 55 of a bar d¹⁰. The ends d of the cylinder D are provided with slot d¹¹, which are parallel with the feelers. Screws d¹², passing through the slots and entering the bar d¹⁰, provide for 60 adjusting the bar toward and from the circumference of the cylinder D. Thus the degree to which the feelers enter the cylinder may be varied to secure the proper positions of the notches l' with reference to the punches 65 M. Then the levers K and rods L L' will be shifted, so as to bring the notches l' of the corresponding rods L' out of line with the

punches M. The descent of the bar L² will cause the punches corresponding to those bars L' whose notches are shifted out of line 70 with the punches to be carried down with it. Those feelers which are opposite imperforate portions of the stencil-sheet will adjust the corresponding rods L' into such a position that the notches l' will be in line with the corresponding punches M, and the latter will not be operated by the descent of the bar L². 75

The punches M work between guide-bars m. The opposite sides of these guide-bars are faced with felt m'. The bars are adjustable toward each other by means of screws m² pressing against said bars and supported by bars m³. The punches work through holes formed in a table m⁴. Any number of sheets of paper to be made into music-sheets may 85 be arranged upon the table and will be cut simultaneously and to correspond with the stencil-sheet.

When the bar H is reciprocated away from the cylinder D, it withdraws all the feelers I 90 from the perforations in the stencil-sheet, so that they will not prevent movement of the latter, and when the bar H is moved forwardly it permits of the described coaction of the feelers with the stencil-sheet. 95

The sheets of paper to be made into music-sheets are fed at the same surface speed as the stencil-sheet. The means for feeding these sheets of paper comprise a ratchet-wheel N, affixed to a shaft N' and journaled in the 100 framework B of the machine and having affixed to it a toothed pinion N². The pinion N² engages with a toothed gear-wheel N³, mounted upon a shaft N⁴, journaled in the framework B of the machine. With the 105 ratchet-wheel N is combined a pawl N⁵, carried by a pawl-lever N⁶, loosely mounted upon the shaft N' and having pivotally connected to it one end of a rod N⁷, which is operated by an eccentric N⁸, carried by the main driving-shaft E. A spring holds the pawl in contact 110 with the ratchet-wheel. Upon the shaft N⁴ are affixed a pair of sprocket-wheels N⁹, with which sprocket-chains N¹⁰ engage. These sprocket-chains also engage with a pair of 115 sprocket-wheels N¹¹, affixed to a shaft N¹², journaled in blocks n, fitted to housings formed in the framework B of the machine and made adjustable in said housings by means of screws n'. The sprocket-chains N¹⁰ are provided with a number of bars n², which may be secured to the chains by screws n³, passing 120 through links of the chains and entering the ends of the bars. These screws also serve as a means for attaching rollers n⁴, which when 125 the links of the chains are in their uppermost position run along tracks n⁵. Above the tracks n⁵ are guides n⁶, which prevent the upper portions of the sprocket-chains from rising out of position. The bars n² are provided with arms n⁷, fitted with rollers n⁸. As 130 may be seen by reference to Fig. 5, the arms n⁷ are made in the form of rods having ends engaged with screw-threads upon their end

portions. The rollers n^8 operate in connection with cams n^9 , affixed to the framework B of the machine above the sprocket-chains and their arms. The arms n^7 pass through slots formed longitudinally in the bars n^2 and have attached to them castings n^{10} , which are shifted with the arms by the operation of the cam n^9 . After the cam n^9 has forced any arm n^7 inward as far as it can do the forward movement of the sprocket-chains carries that arm n^7 into a guideway n^{11} , and while the said arm n^7 travels along this guideway it is maintained in that position upon its bar n^2 , onto which it is adjusted by the cam n^9 . After the said arm is carried out of the guideway n^{11} by its bar n^2 through the agency of the sprocket-chains the said arm n^7 will come in contact with a reverse cam n^{12} , which will slide the arm outwardly along its bar n^2 to the position which it occupied upon said bar before having been shifted by the cam n^9 . The movement of the arm n^7 lengthwise of the bar n^2 effects a similar movement of the castings n^{10} . In each casting n^{10} is a rod n^{13} , provided at one end with an antifriction-roller n^{14} , which coacts with the under side of a plate n^{15} , fastened to the framework B of the machine. The lower end of each rod n^{13} has a clamping head or disk n^{16} at the end opposite to that which is provided with the roller n^{14} . Both ends of the bars n^2 are provided with arms n^7 , rollers n^8 , castings n^{10} , rods n^{13} , antifriction-rollers n^{14} , and clamping heads or disks n^{16} , and both of the sets of these parts for the two ends of the bars n^2 are combined with cams n^9 , guideways n^{11} , cams n^{12} , and plates n^{15} .

Sheets of paper to be manufactured into music-sheets are guided by suitable guides and pass under the plate n^{15} and upon the bars n^2 , carried by the sprocket-chains. As the edges pass under the plate n^{15} the arms n^7 will be shifted away from the ends of the bars n^2 sufficiently to carry the clamping heads or disks n^{16} over the edges of the paper, and when the rods n^{13} pass beneath the plates n^{15} the clamping heads or disks will be forced down upon the sheets of paper, so as to securely clamp them to the bars n^2 . The paper will be released after the passage of the rod n^{13} beyond the plate n^{15} .

The operation of the machine is as follows: A roll A, carrying a stencil-sheet, is mounted in the uprights b, and its end portion, which is not cut with note-perforations, passed around the cylinder D and its end fastened to the roll G. The end portion is, however, preferably provided with marginal apertures which fit over the sprockets d^2 . The paper to be cut is first brought under the punches M and its end fastened to a bar or bars N^2 of the traveling chain N^{10} by the clamping means thereon. The main shaft E is then started, and through it the sprockets d^2 are intermittently operated to feed the stencil-sheet around the cylinder. At the same time the chain N^{10} is intermittently moved, which

brings successive bars n^2 under the paper and their clamps into position to be automatically operated by the stationary cams n^{11} and n^{15} . As the stencil-sheet is fed over the cylinder the note-perforations are brought into alignment with the feelers, and as each transverse line of perforations is brought into line with the feelers the feelers are permitted to move forward toward the stencil-sheet. Only those feelers pass through the stencil-sheet which are before openings, and this movement of each feeler sets its slide-rod to cause its punch to be forced through the paper sheets which are being formed into music-sheets. After the operation of the punches all of the feelers are withdrawn and a feeding forward of the stencil-sheets and music-sheet takes place. After the stencil-sheet has unwound from the roll A it is rewound thereon. Another stencil-sheet may then be substituted.

What I claim as my invention, and desire to secure by Letters Patent, is—

1. In a machine for cutting music-sheets, the combination of a stationary support over which a stencil-sheet is passed, and having openings or recesses in line with the perforations of the stencil-sheet, means comprising a slipping take-up roll and a pawl-and-ratchet mechanism operating intermittently to feed the stencil-sheet, means for intermittently feeding a number of sheets of paper to be formed into music-sheets, and a number of punches for cutting the music-sheets and controlled by the stencil-sheet.

2. In a machine for cutting music-sheets, the combination of a stationary support over which a stencil-sheet is passed, and having openings or recesses in line with the perforations of the stencil-sheet, means for moving the stencil-sheet, means for feeding a number of sheets of paper to be formed into music-sheets, a number of punches for cutting the music-sheets and controlled by the stencil-sheet, and a pair of adjustable bars between which said punches work.

3. In a machine for cutting music-sheets, the combination of a stencil-sheet having marginal openings, a support over which the stencil-sheet passes, sprockets with which the marginal openings coact, means for intermittently moving the sprockets, a number of feelers controlled by the stencil-sheet, means for moving the feelers toward the stencil-sheet and means for withdrawing them therefrom, reciprocating punches controlled by the feelers, and an intermittently-operated means for moving a plurality of sheets of paper past said punches.

4. In a machine for cutting music-sheets, the combination of a support for a stencil-sheet, means for feeding the stencil-sheet, a number of feelers controlled by the stencil-sheet, a slide-rod provided for each feeler, consisting of a plurality of sections which have a loose connection one with the other, and one of which sections is provided with a

- notch, means for vertically reciprocating the notched portion of the slide-rods and a number of punches controlled by said notched portions.
5. In a machine for cutting music-sheets, the combination of a support for a stencil-sheet, means for feeding the stencil-sheet, a number of feelers controlled by the stencil-sheet, a number of punches controlled by the 70
10 feelers, means comprising a number of traveling bars for feeding the music-sheets and means automatically operated carried by each bar for securing the music-sheets on said bars.
6. In a machine for cutting music-sheets, 15 the combination of a support for a stencil-sheet, means for feeding the stencil-sheet, a number of feelers controlled by the stencil-sheet, a number of punches controlled by the feelers, means comprising a number of traveling bars for feeding the music-sheets, clamps carried by each of said bars for securing the music-sheets at their edges, and stationary cams with which said clamps engage 80
20 in their movement with the bars for moving 85
25 said clamps over the edges of the music-sheets and forcing them down upon the same.
7. In a machine for cutting music-sheets, the combination of a support for a stencil-sheet, means for feeding the stencil-sheet, a 90
30 number of feelers controlled by the stencil-sheet, a number of punches controlled by the feelers, means comprising sprocket-wheels, sprocket-chains and a number of traveling bars connected to the sprocket-chains for 95
35 feeding the music-sheets, and automatic cam-operated means for securing the music-sheets on said bars.
8. In a machine for cutting music-sheets, 100
40 the combination of a support for a stencil-sheet, means for feeding the stencil-sheet, a number of feelers controlled by the stencil-sheet, a number of punches controlled by the feelers, means comprising sprocket-wheels, sprocket-chains and a number of traveling 105
45 bars connected to the sprocket-chains for feeding the music-sheets, ratchet mechanism for intermittently rotating the sprocket-wheels and automatic cam-operated means for securing 110
50 the music-sheets on said bars.
9. In a machine for cutting music-sheets, 115
55 the combination of a support for a stencil-sheet, means for feeding the stencil-sheet, a number of feelers controlled by the stencil-sheet, a number of punches controlled by the 120
60 feelers, means for feeding the music-sheets comprising a number of traveling bars, arms fitted to the sliding bars to slide lengthwise thereof and having supports for clamping-rods, which rods are capable of being moved 125
65 transversely to said bars, cams for sliding said arms lengthwise on said bars, and means for moving the clamps transversely to said bars.
10. In a machine for cutting music-sheets, 130
65 the combination of a support for a stencil-sheet, means for feeding the stencil-sheet, a number of feelers controlled by the stencil- sheet, a number of punches controlled by the feelers, means for feeding the music-sheets comprising a number of traveling bars, arms fitted to the sliding bars to slide lengthwise thereof and having supports for clamping-rods, which rods are capable of being moved transversely to said bars, cams for sliding said arms lengthwise on said bars and cams for moving the clamps transversely to said bars.
11. In a machine for cutting music-sheets from a stencil-sheet, the combination with a perforated support for a stencil-sheet, means 80
120 for feeding the stencil-sheet, a number of feelers controlled by said sheet, a pivoted lever connected at one end to each of the feelers, a pair of rods connected to the other end of each lever, which rods have a loose connection with each other, and one of which is provided with a notch, a bar through which said notched rods move longitudinally, punches carried by said bar and adapted to coact with said notched rods, and means for reciprocating said bar.
12. In a machine for cutting music-sheets from a stencil-sheet, the combination with a perforated support for a stencil, means for feeding the stencil-sheet, a number of feelers controlled by said sheet, a pivoted lever connected at one end to each of said feelers, a pair of rods connected to the other end of each lever, which rods have a loose connection with each other, and one of which is provided with a notch, a bar through which said notched rods move longitudinally, a spring connected to each notched rod for causing a movement of its feeler toward the stencil-sheet, a bar through which the feelers extend, which bar has connected with it means to move it toward and away from the stencil-sheet, punches carried by the bar carrying the notched rods, and means for reciprocating the bar carrying the punches.
13. In a machine for cutting music-sheets, the combination with a perforated support for a stencil-sheet, means for feeding the stencil-sheet, a number of feelers controlled by the stencil-sheet, an adjustable stop for limiting 115
140 the distance to which the feelers shall project through the perforated support, a number of slide-bars controlled by the feelers and having notches, and a number of punches controlled by the slide-bars.
14. In a machine for cutting music-sheets, a support for a stencil-sheet provided with grooves or recesses, and means for adjusting the depth of said grooves or recesses.
15. The combination of a support provided 125
160 with grooves or recesses, means for passing a stencil-sheet over said support, feelers controlled by the stencil-sheet and connected to notched bars, punches actuated by said bars, and means for varying the depth of the 130
165 grooves or recesses in said support, whereby the relative positions of the punches and the notches in said bars may be adjusted.
16. The combination of a support and means

for passing a stencil-sheet over the same, feelers controlled by said stencil-sheet, and positive means independent of the stencil-sheet for withdrawing the feelers from the perforations in the stencil-sheet.

17. The combination of a support and means for passing a stencil-sheet over the same, feelers controlled by said stencil-sheet, a slide-rod mechanically connected to each feeler, consisting of sections having a loose connection one with the other, one of which sections

is provided with a notch, means connected to the notched portions of the slide-rods for vertically reciprocating the same, and punches controlled by said notched portions. 15

In testimony whereof I have signed my name to this specification in the presence of two subscribing witnesses.
